UNITED STATES PATENT OFFICE.

LOUIS V. ARONSON, OF NEWARK, NEW JERSEY, ASSIGNOR TO ART METAL WORKS, INC.,
A CORPORATION OF NEW JERSEY.

DESIGN FOR AN ATOMIZER OR SIMILAR DEVICE.

Application filed May 18, 1929. Serial No. 31,277. Term of patent 14 years.

To all whom it may concern:

Be it known that I, LOUIS V. ARONSON, a citizen of the United States, residing at Newark, in the county of Essex and State of New Jersey, have invented a new, original, and ornamental design for Atomizer or Similar Device, of which the following is a specification, reference being had to the accompanying drawing, forming part thereof, wherein:—

Figure 1 is an end elevational view looking at one end of the atomizer shown in Fig. 2;

Fig. 2 is a side elevational view of the atomizer;

Fig. 3 is an end elevational view looking at the other end of the atomizer shown in Fig. 2;

Fig. 4 is a plan view of the atomizer shown in Figs. 1, 2 and 3;

Fig. 5 is a bottom view of the atomizer shown in Figs. 1, 2, and 3; and

Fig. 6 is a perspective view of the atomizer with the parts in atomizing position.

I claim:

The ornamental design for an atomizer or similar device substantially as shown and described.

LOUIS V. ARONSON.
